UNITED STATES PATENT OFFICE.

ISAAC B. KLEINERT, OF NEW YORK, N. Y., ASSIGNOR TO I. B. KLEINERT RUBBER COMPANY, A CORPORATION OF WEST VIRGINIA.

ABDOMINAL HOSE-SUPPORTER.

No. 795 841.

Specification of Letters Patent.

Patented Aug. 1, 1905.

Application filed February 10, 1905. Serial No. 245,100.

To all whom it may concern:

Be it known that I, ISAAC B. KLEINERT, a citizen of the United States, and a resident of the borough of Manhattan, in the city, county, and State of New York, have invented certain new and useful Improvements in Abdominal Hose-Supporters, of which the following is a specification.

My invention relates to abdominal hose-supporters—that is, to those hose-supporters in which a broad pad is employed, together with means for firmly pressing the pad against the abdomen of the wearer in connection with the stocking-supporting device. Heretofore such a pad has been made and provided with depending straps adapted to engage the hem or upper edge of the stockings, the pad being provided with a band which passed around the waist of the wearer. This means is effective to hold the pad in position, but on account of the strain produced at the small of the wearer's back is quite painful and unhealthful. Such pressure tends to force the body forward to an awkward position and eventually to produce serious injury. In my device the pad is suspended from the corsets, so that no strain is produced upon the back.

My invention further consists in adapting the device to corsets of different shapes.

The accompanying drawing represents an abdominal hose-supporter embodying my invention, in which—

1 is the pad, provided with corset-engaging means at its central upper edge, shown as an eye 11, adapted to engage with any stud, preferably the lower stud, of the corset. As shown, the pad 1 is also provided adjacent each of its edges with a vertically-disposed flat tubular casing 12, adapted to receive and snugly pass a stocking-supporting strap 2, the upper end of which is provided with any desired form of clip 21, adapted to embrace and engage the lower edge or hem of the corset. Additional straps 3, shown as two in number, are firmly secured at their upper ends to the pad 1 intermediate the casings 12. All the straps 2 and 3 have suitable stocking-engaging means 4 at their lower ends and are preferably provided with buckles 5, by which their length may be adjusted. It is of course understood that the straps 2 and 3 are ordinarily elastic, so as to prevent sudden strain or tearing of the garments.

If all corsets were of substantially the same dip or angle at their lower edges and had the

stud at the same distance from the lower front point, it would be possible to secure the fastenings 21 rigidly to or adjacent the outer upper corners of the pad 1. In practice, however, the shape of the corset and the position of the stud thereon vary, so that it is of the greatest advantage to produce an even strain and the proper pressure of the pad against the person of the wearer that the distance from the upper edge of the pad to the connection 21 be variable. In this way an even strain on the connections 11 and 21 is possible. By passing the straps 2 through the casings 12, so as to permit their vertical or longitudinal adjustment therewith, the pad is relieved of a portion of the strain, which is transferred directly to the engaging devices 21, and the pad is securely held in position, while by means of the slides or buckles 5 the vertical strain may be divided as desired between the straps 2 and 3.

Having thus described my invention, what I claim, and desire to secure by Letters Patent, is—

1. An abdominal hose-supporter comprising an abdominal pad, corset-engaging means adjacent the upper edge of said pad approximately midway of its width, additional means for positively engaging a corset adjustably connected with said pad at each side of said first-named means, and stocking-supporting straps depending from said pad.

2. An abdominal hose-supporter comprising an abdominal pad, corset-stud-engaging means adjacent the upper edge of said pad midway of its width, clips for engaging the lower edge of the corset having relative vertically-adjustable connection with said pad at each side of said stud-engaging means, and stocking-supporting straps depending from said pad.

3. An abdominal hose-supporter comprising an abdominal pad, corset-stud-engaging means on said pad, additional means for positively engaging a corset having relative vertically-adjustable connection with said pad adjacent each of its outer edges, and stocking-supporting straps depending from said pad.

4. An abdominal hose-supporter comprising an abdominal pad, means for positively engaging a corset adjustably connected with said pad adjacent each of its outer edges, separate corset-engaging means on said pad intermediate said connections, and stocking-supporting straps depending from said pad.

5. An abdominal hose-supporter comprising hose-supporting straps having means for positively engaging a corset at their upper ends, an abdominal pad extending between and vertically adjustable on said straps, and means for securing said pad on the corset.

6. An abdominal hose-supporter comprising hose-supporting straps having means for positively engaging a corset at their upper ends, an abdominal pad extending between and vertically adjustable on said straps, and corset-engaging means on said pad intermediate said straps.

7. An abdominal hose-supporter comprising an abdominal pad, corset-engaging means adjacent the upper middle portion of said pad, stocking-supporting straps depending from said pad, and additional stocking-supporting straps having means for positively engaging a corset at their upper ends and having relative adjustable connection with said pad adjacent its outer edges for holding the pad in position.

8. An abdominal hose-supporter comprising

an abdominal pad, corset-engaging means adjacent the upper middle portion of said pad, stocking-supporting straps depending from said pad, additional stocking-supporting straps having means for positively engaging a corset at their upper ends, and vertically-adjustable connections between said straps and the outer edges of said pad for holding the pad in position.

9. An abdominal hose-supporter comprising an abdominal pad, corset-engaging means adjacent the upper edge of said pad, stocking-supporting straps depending from said pad, vertical casings adjacent the outer edges of said pad, and corset-engaging stocking-supporting straps vertically adjustable in said casings.

In testimony whereof I have signed this specification in the presence of two subscribing witnesses.

ISAAC B. KLEINERT.
